UNITED STATES PATENT OFFICE.

WILLIAM T. CARROLL, OF WORCESTER, ASSIGNOR TO GEORGE DRAPER & SONS, OF HOPEDALE, MASSACHUSETTS.

SPINDLE-BOLSTER.

SPECIFICATION forming part of Letters Patent No. 327,135, dated September 29, 1885.

Application filed April 27, 1885. (No model.)

To all whom it may concern:

Be it known that I, WILLIAM T. CARROLL, of the city and county of Worcester, State of Massachusetts, have invented an Improvement in Spindle-Bolsters, of which the following description, in connection with the accompanying drawings, is a specification, like letters on the drawings representing like parts.

10 In that class of spindle and bearings wherein the bolster and foot-step are both located below or one within the whirl, the bolster has depended for its main lateral support upon a metal sleeve erected upon or forming part 15 of a hub or base held in the step-rail and chambered to contain oil and constitute an oil-well.

To prevent the injurious gyration of spindles when running at high speed, the bolster 20 between its external surface and the interior of the said sleeve has been surrounded by an elastic or yielding jacket or packing usually composed of fibrous material, but sometimes of oil alone, such jacket or packing permitting 25 the bolster to yield freely in any direction laterally when the spindle is finding its true center of rotation.

In my experiments, to avoid the employment of a loose bolster, and consequently of 30 special means to restrain its rotation with the spindle, and also to obviate the use of an elastic or yielding packing of the class referred to, which has frequently to be renewed, and also to lighten the weight of metal in spinning, I have discovered that a bolster supported externally above the rail and at a point 35 within a sleeve-whirl by a non-metallic bolster-holder does not need to have the bolster inclosed or surrounded by an elastic packing, either of fibrous material or of oil.

40 My invention therefore consists, essentially, in a spindle-bolster, and a hub or base, and an intermediate non-metallic bolster-holder to sustain the said bolster externally, thus deadening vibration.

45 Figure 1 represents a spindle and its supports embodying my invention, the spindle being in elevation, while its sleeve and the parts surrounded by and below it are in section; and Figs. 2 and 3 are modifications of my invention, to be referred to.

The spindle A, with its attached sleeve-whirl A', and the rail B, are of usual construction.

The hub or base C, inserted in a socket of 55 the rail B, and there confined, has a head or enlarged part, which forms part of the oil-well and receives a foot-step, a.

Extended above the hub or base C and connected therewith is a non-metallic bolster-holder, d, made as a tube, in the upper end of which is fitted the metal bolster e, in which the pintle of the spindle enters, the lower end thereof resting upon the foot-step a, the non-metallic bolster-holder entering the sleeve- 65 whirl, and being extended therein preferably up to or above the line of the band-pull on the whirl. Among the non-metallic substances which I have found to answer well for the bolster-holder are wood, celluloid, and vulcanized 70 fiber. Instead of these materials I may use any other well-known non-metallic substances having substantially the same degree of elasticity and possessing the quality of not being injuriously affected by oil.

75 I have embodied my invention practically in several different forms—as, for instance, the hub or base C shown in Fig. 1 may be a non-metallic substance—such as wood or vulcanized fiber—and if the non-metallic substance 80 employed is the same as that of which the bolster-holder is composed, then the said bolster-holder and hub or base may be made integral, as in Figs. 2 and 3.

The lower end of the hub or base may be 85 screw-threaded and be held in the rail by the usual nut, g, or be acted upon directly by a set-screw, f, as in Fig. 2; or, if desired, the said end may be placed in a sleeve, h, slotted at one side from end to end, as at the left of Fig. 90 3, the latter serving as a clamp, which may be contracted by means of a set-screw, f.

I desire it to be understood that the hub or base C shown in Fig. 1 may be of metal.

The non-metallic bolster-holder d, extended 95 above the hub or base, possesses an amount of elasticity sufficient to yield to the requirements of a rapidly-rotating spindle, thus deadening its vibration due to an unbalanced load. The non-metallic bolster-holder shown in 100 Fig. 1 is made as a tube having a close fit at its lower end, between the hub or base and the

foot-step; but in Figs. 2 and 3 the said holder *d* is integral with the hub or base.

In the drawings, the bolster *e* is a fit in the non-metallic bolster-holder, and the lower end 5 of the bolster rests on the foot-step; but this is not a necessity, for the weight of the bolster may be supported by the collar at its upper end resting on the top of the bolster-holder.

I am aware that a bolster has been supported 10 in a yielding manner by india-rubber placed in a step, as in United States Patent No. 82,049, September 8, 1868, for a centrifugal machine, and I do not claim such a support. In my invention the bolster-holder—the non- 15 metallic member or element—is extended above the hub or base and in its upper part holds the bolster.

I claim—

A spindle-support composed of a hub or base, a bolster, and a non-metallic bolster- 20 holder held by and extended above the said base, the said holder embracing and holding the bolster externally at a point above the top of the hub or base, to operate substantially as described.

In testimony whereof I have signed my name to this specification in the presence of two 25 subscribing witnesses.

WILLIAM T. CARROLL.
